UNITED STATES PATENT OFFICE

ROBERT EAMES, OF DETROIT, MICHIGAN

FRUIT JAR CAP REMOVER

Application filed September 22, 1930. Serial No. 483,638.

The present invention relates to a device for removing fruit jar caps and the like and has for its prime object to provide a device of this nature which may be permanently 5 mounted under a shelf or the like so that the fruit jar cap may be engaged therein and both hands used on the jar to unscrew the same from the cap.

A still further very important object of 10 the invention resides in the provision of a device of this nature which is extremely simple in its construction, inexpensive to manufacture, strong and durable, thoroughly efficient and reliable in use and otherwise 15 well adapted to the purpose for which it is designed.

With the above and numerous other objects in view as will appear as the description proceeds, the invention resides in certain 20 novel features of construction, and in the combination and arrangement of parts as will be hereinafter more fully described and claimed.

In the drawings:—

25 Figure 1 is a fragmentary front elevation of a pantry or kitchen dresser showing my device mounted under a shelf thereof.

Figure 2 is a sectional view taken substantially on the line 2—2 of Figure 1 to illustrate the location of the device.

Figure 3 is a top plan view of the device.

Figure 4 is a rear elevation thereof.

Figure 5 is a sectional view taken substantially on the line 5—5 of Figure 3.

35 Figure 6 is a transverse sectional view taken through the limbs of the device as shown in Figure 3.

Referring to the drawings in detail, it will be seen that the device is in the form of a 40 substantially U-shaped body having a cross portion 5 and sides 6. The sides 6 are formed with downwardly offset flanges 7 and 8, the inner or opposed edges of which converge rearwardly toward each other and the said 45 edge of the flange 8 is formed with a plu-

rality of teeth 9. Each of the flanges 7 and 8 is connected with the outer part of each limb of the U-shaped member by a downwardly and inwardly sloping part 11 and the bight part 5 has its ends connected with the 50 inner edges of the flanges 7 and 8 by the outwardly and downwardly sloping parts 5'. Thus when the device is fastened to the under part of the shelf or the like, shown at 10, by nails or the like passing through holes 55 11' in the outer edges of the leg portions and the bight part the flanges 7 and 8 will be spaced from the shelf so that a jar 12 can be placed in engagement with the free edges of the flanges 7 and 8 without interference 60 from the shelf.

A fruit jar may be lifted and its cap inserted between the opposed edges of the flanges 7 and 8 and then the fruit jar turned so as to unscrew it from its cap, it being 65 understood that the cap will be wedged between the flanges 7 and 8 and the teeth 9 will bite into the cap sufficiently to prevent the same from slipping.

It is thought that the construction, utility 70 and advantages of the present invention will now become apparent to those skilled in this art without a more detailed description thereof. The present embodiment of the invention has been disclosed in considerable detail 75 merely for the purpose of exemplification since in actual practice it attains the features of advantage enumerated as desirable in the statement of the invention and the above description. It will be apparent that 80 changes in the details of construction, and in the combination and arrangement of parts may be resorted to without departing from the spirit and scope of the invention as hereinafter claimed or sacrificing any of its advantages.

Having thus described my invention, what I claim as new is:—

A device of the class described comprising 90 a substantially U-shaped body, the inner sides

of the limbs of which are formed with offset flanges extending inwardly toward each other, said flanges terminating in edges which converge toward each other in the 5 direction of the cross member of the body, and one of the edges being formed with a plurality of teeth and means whereby the outer portions of the legs and the bight of the U-shaped member can be fastened to the 10 under part of a shelf or the like.

In testimony whereof I affix my signature.
ROBERT EAMES.
